INVENTOR

Louis Nordlinger,

BY

Joseph H. Levy

ATTORNEY

UNITED STATES PATENT OFFICE.

LOUIS NORDLINGER, OF NEW YORK, N. Y., ASSIGNOR TO THE NORDLINGER-CHARLTON FIREWORKS COMPANY, OF SAME PLACE.

FIRE-CRACKER.

SPECIFICATION forming part of Letters Patent No. 634,180, dated October 3, 1898.

Application filed January 27, 1898. Serial No. 668,111. (No model.)

To all whom it may concern:

Be it known that I, LOUIS NORDLINGER, a citizen of the United States, residing in New York, county of New York, and State of New York, have invented certain new and useful Improvements in Fire-Crackers, of which the following is a specification.

My invention has for its object to provide an improved charge and stem in fire-crackers and the like which may be used with the ordinary form of cracker shell or body, or preferably a shell or body which is substantially tubular in form and having a chamber to receive the explosive charge, the ends of the body being contracted to substantially close or choke said chamber, so as to retain the charge and resist the sudden exit of the explosive. The stem and charge of explosive are preferably found in a single structure which is adapted to fit within the body or chamber of a fire-cracker or other analogous firework. In carrying out this portion of my invention I provide a structure of inflammable material, such as paper, having an enlarged chamber to receive a charge and an attenuated or reduced portion or stem extending therefrom in tubular form and containing powder that is in communication with said charge.

Reference is to be had to the accompanying drawings, forming part hereof, wherein—

Figure 1 is a side elevation of a fire-cracker embodying my invention. Fig. 2 is a vertical section thereof, and Fig. 3 is a side elevation of the combined charge and stem structure.

In the accompanying drawings, in which similar numerals of reference indicate corresponding parts in the several views, 1 indicates the body portion of a fire-cracker. By preference this body is made of one or more convolutions or windings of paper or other suitable material 2. It is made in tubular form to produce a chamber 3 to receive an explosive charge 4. At one or both ends of the chamber 3 the body 4 is contracted to substantially close the ends of said chamber, whereby necks or chokes 5 are produced to confine the charge 4. This contraction of the body 1 to form the chokes 5 may be made by wetting or dampening the material 2 and then compressing the same in annular form

or circumferentially, thus forming the annular chokes 5 and external grooves 6.

In making the fire-cracker the charge 4 is placed within the body 1 while the latter is 55 in tubular form and the stem 7 connected with said charge, and then the ends of the chamber 3 are closed in manner set forth.

It is clear that my improved charge and stem may be employed in any desirable form, 60 but I prefer the form illustrated in Figs. 1 and 2 for manifest reasons.

In my improved form of charge and stem they are both made in a single structure, as follows: I take paper or other suitable inflammable material and wind it in such manner as to produce an enlarged portion or pocket 8, and at the ends of said pocket the material is wound in considerably smaller or attenuated form to provide the stem 7, and 70 said pocket and stem are filled with a proper explosive—such, for instance, as gunpowder. A pocket and stem thus formed and charged are then placed in the body 1, as shown in Fig. 2, and the chokes 5 formed at the ends 75 of such pocket or charge to confine the same within the body of the fire-cracker.

As indicated in Fig. 3, the charges and stems are made in continuous or long lengths, and then the stems are severed between two of 80 such pockets, whereby a pocket or charge and an attached stem are formed suitable for an individual fire-cracker.

The paper or other inflammable material to form the pocket 8 and stem 7 is shown arranged in spiral form and arranged to bring one stem 7 between two pockets 8, or vice versa. Of course by making these pockets and stems in long continuous lengths it is cheaper than making each pocket and stem 90 independently; but it will be understood that the latter course may be pursued, if desired.

It is evident that a neck 5, such as described, may be provided at one end of the body 1 and the opposite end plugged or 95 choked in any ordinary or suitable manner.

I do not limit my invention to the precise details of construction shown and described, as they may be varied without departing from the spirit thereof. For example, it is 105 not essential to the formation of the combined stem and charge, although highly de-

sizable, that the stem portion shall contain an explosive, as such stem may be impregnated with some highly-combustible material as a substitute for the powder and the latter omitted from that portion.

Having now described my invention, what I claim is—

1. A fire-cracker comprising a body having a chamber for an explosive charge, an explosive within said chamber, a stem leading from said explosive, and a choking neck or contraction formed in the body of the fire-cracker at the end of the charge to confine the latter in the body, substantially as described.

2. A fire-cracker comprising a body having a chamber for an explosive charge, an explosive within said chamber, a stem leading from said explosive, and choking necks or contractions formed in the body of the fire-cracker at the ends of the charge to confine the latter in the body, substantially as described.

3. A fire-cracker comprising a body composed of one or more windings or convolutions of material having a chamber for an explosive charge, an explosive therein, a stem connected with said explosive, and a choking neck or contraction at the end of said chamber formed by an annular depression in the walls of said body, substantially as described.

4. A fire-cracker comprising a body having a chamber for an explosive charge, and a pocket for a charge and stem connected with said body, said pocket and stem being in a single structure, the pocket of said structure that contains the charge being of greater area than the stem portion, substantially as described.

5. A charge and stem for a fire-cracker com-

prising a pocket for the charge having its walls and two ends integral and a reduced or attenuated portion for the stem, all made in a single structure and filled with an explosive, substantially as described.

6. A charge and stem for a fire-cracker comprising a pocket, and a reduced or attenuated stem portion composed of inflammable material made in a single structure and filled with an explosive, substantially as described.

7. A charge and stem for a fire-cracker composed of a pocket having its walls and two ends integral and a stem formed from a winding of inflammable material all made in a single structure, the pocket being larger than the stem and filled with an explosive, substantially as described.

8. A charge and stem for a fire-cracker composed of an inflammable material wound in spiral form in a single structure, the pocket having its walls and two ends integral and being larger than the stem and both filled with an explosive, substantially as described.

9. A charge and stem for a fire-cracker composed of an inflammable material having a plurality of pockets and a plurality of intermediate reduced or attenuated portions between said pockets, all the pockets being filled with an explosive, whereby the stems may be cut to form independent charges and stems, substantially as described.

Signed at the city, county, and State of New York this 26th day of January, 1898.

LOUIS NORDLINGER.
